UNITED STATES PATENT OFFICE.

NIS JOHNSON AND AUGUSTUS H. JONES, OF MERIDEN, CONNECTICUT, AS-SIGNORS TO THE MERIDEN BRONZE COMPANY, OF SAME PLACE.

CENTRAL-DRAFT LAMP.

SPECIFICATION forming part of Letters Patent No. 564,017, dated July 14, 1896.

Application filed August 7, 1893. Serial No. 482,597. (No model.)

To all whom it may concern:

Be it known that we, NIS JOHNSON and AUGUSTUS H. JONES, of Meriden, in the county of New Haven and State of Connecticut, have 5 invented a new Improvement in Central-Draft Lamps; and we do hereby declare the following, when taken in connection with accompanying drawings and the letters of reference marked thereon, to be a full, clear, and 10 exact description of the same, and which said drawings constitute part of this specification, and represent, in—

Figure 1, a vertical sectional view of a central-draft lamp embodying our improvements, 15 the draft-tube being broken away to more clearly disclose the construction of the wick-carrier; Fig. 2, a detail view of the upper end of the tubular guide and operating-rod, viewed in the direction indicated by the arrow, Fig. 1; Fig. 3, an enlarged detail showing 20 a portion of the draft-tube and the combined secondary perforated air-distributer and drip-trough; Fig. 4, a detail view showing the combined secondary air-distributer 25 and drip-trough in plan within the draft-tube, the latter being broken away to disclose the discharge-openings.

Our invention relates to a central-draft lamp, and especially to improvements in the 30 means for adjusting the wick, in the wick-raiser, and in the means for distributing the air and permitting the return of oil to the wick, its objects being to produce a simple, convenient, and effective device, possessing 35 advantages over lamps of a similar type.

With these ends in view our invention consists in certain details of construction and combinations of parts, as will be herein-after described, and then particularized in the 40 claims.

In the drawings we have shown an ordinary "mammoth" lamp-fount A, mounted on its customary perforated base A', and provided with the central-draft tube B. At one side 45 of the lamp-fount A is located a tubular guide C, which extends completely through the same, at both its lower end c and its upper end c', said ends projecting from the lamp-fount. The upper end c' of the guide C is 50 constructed so as to take into the screw-threads d, of coarse pitch, formed on the

vertical operating-rod D near its upper end. This operating-rod D extends beyond both ends of the guide C, and at its lower end is provided with a milled knob E, whereby it 55 may be rotated within the said guide. The upper end of the rod D is provided with a button F, which is received by screw-threads f, formed on the same above the coarse threads d. The particular construction 60 whereby the upper end c' of the tubular guide C is adapted to take into the coarse screw-threads d may, of course, vary—as, for instance, instead of the short spiral ribs C' upset on its inner surface, it may have in- 65 wardly-projecting points or studs.

The upper end of the operating-rod D swivels or turns in a head or disk G, located at the upper end of the draw-bar H, which passes into the lamp-fount and is provided 70 with means for raising the wick. The lateral stem h, at the lower end of the draw-bar H, passes through a vertical slot I, formed in the fixed tubular section J, which depends from the top of the lamp-fount and is concentric with the draft-tube B, and coincident with the neck of the fount, to which it corresponds in diameter, whereby a large annular chamber J' is formed between it and the draft-tube. A tubular section K, attached 75 to the stem h of the draw-bar, telescopes within the tubular section J. These tubular sections J K are therefore much larger than the ordinary wick-band, and they dispense with the same. Struck out of the inner tubular section K, so as to leave vertical openings k, are vertical wick-holding jaws L, formed at their upper ends with outwardly-bulged bearing portions M, and toothed inwardly-projecting lips m, which bite into or engage 85 the wick. The jaws L, while they are shown as integral with the inner telescopic section K, it is evident that they may be formed separate therefrom and attached thereto, but in either case they are to be made of spring 90 metal.

The natural tendency of the jaws is to spring outward, but the contact of the bulged bearing portions M with the inner wall of the outer fixed telescopic section J forces the 100 toothed lips m into the wick. When, however, the draw-bar H is raised by the operat-

ing-rod E to the position to release the jaws from the wick, the said jaws will be permitted to spring outward from the wick, by reason of the clearance spaces or openings N in the upper end of the section J, which receive the bulged bearing portions M when the latter are in range with them. In the act of raising the wick the lower projecting end c of the guide C forms a stop for the impingement of knob E when the jaws have been released from the wick. When the operating-rod D is lowered, the jaws are caused to again move inwardly, so as to engage the wick, by the inclines m' formed on the under side of the bulged bearing portions M being forced in contact with the bottom edges of the clearance spaces N.

It is designed that the pitch of the screw d should be such as to cause the rod D to rotate under pressure exerted on the button F, thus permitting the rod to be plunged or shoved down quickly, so as to have the advantage of a plunge and screw. Such construction is not claimed herein as broadly new, but only where the operating-rod turns within and is raised and lowered in a fixed guide. By constructing the wick adjuster or raiser with these two collars J K, the lamp can be easily wicked, and an ordinary instead of a special wick may be employed.

At the upper end of the draft-tube B is the customary perforated air-distributer O, having the deflector P at the top. A short distance below the top of the draft-tube is an internal annulus or ring Q, which flares downwardly, and at its lower end is provided with a horizontal peripheral flange q, whereby it is firmly secured to the inner wall of the said tube. The lower edge of the air-distributer O rests on this flange q. The upper end of the annulus or ring has an upwardly-projecting vertical annular flange r. Between the flanges q and r the said annulus or ring is furnished with perforations R, through which the air passes, and whereby it is equally distributed in its passage to the air-distributer O. It will be noted that this annulus or ring constitutes what we may term a secondary air-distributer, and at the same time serves as a drip-trough to catch the oil dripping from the wick. The flange q is, of course, imperforate, and the oil dripping thereupon will be permitted to escape back into the lamp-fount through the medium of the discharge-openings s, made in the draft-tube B.

Although we have shown our improvements applicable to what is called a "mammoth" lamp, yet we do not limit ourselves thereto, as they may be applied to smaller lamps having their wicks adjusted from the top of the founts. We do not limit ourselves to the precise form of devices herein shown, as other and different constructions may be adopted and may be resorted to by skilled mechanics without departing from the scope and spirit of our invention. We are aware, however, that it is old to construct a wick-adjusting device which provides for plunging and lifting

the wick by the direct action of a draw-bar, and also for effecting a close or fine adjustment of the wick by turning a finger-button. We are also aware that it is old to engage a wick located upon a central draft-tube by means of spring wick-gripping jaws carried by a wick-holder and normally held in their gripping positions, but allowed to retire and release the wick when the wick-holder is raised in the lamp-fount to a predetermined elevation. We are also aware that a wick-adjusting device containing an operating-rod projecting above and below the lamp-fount and adapted to be operated either by its upper or lower end, and located within a bearing-tube also mounted in the fount, is old. We do not, therefore, claim either of those constructions broadly.

Having fully described our invention, what we claim as new, and desire to secure by Letters Patent, is—

1. In a central-draft lamp, the combination with the fount and central draft-tube thereof, of a vertically-arranged non-rotatable guide-tube permanently mounted in the fount and fixed at its upper and lower ends thereto, an externally screw-threaded longitudinally-movable, revoluble operating-rod located within and projecting above and below the ends of the said guide-tube, which takes into the threads of the rod, an operating-knob or button located at the projecting lower end of the operating-rod, for operating the same, a wick-holder combined with the central draft-tube, and movable up and down thereupon, a draw-bar constructed and arranged independent of the guide-tube, connected at its lower end with the wick-holder, passing through the upper portion of the lamp-fount at a point between the neck thereof and the guide-tube, and having its upper end turned outward and furnished with a head having a central vertical perforation through which the upper end of the operating-rod projects, and in which the said rod is free to turn; and a button applied to the projecting upper end of the rod, and bearing on the upper face of the said head, rotating with the rod and coupling the same with the draw-bar, the threads of the rod being so coarse as to permit it to be plunged up and down through the medium of the draw-bar, in the head of which it then rotates idly in one direction or the other, substantially as described.

2. In a central-draft lamp, the combination with the fount and central draft-tube thereof, of a fixed tubular section extending down into the fount from the neck thereof to which it corresponds in diameter, and constructed near its upper end with clearance spaces, a vertically-movable tubular section fitting within the said fixed section which forms a guide for it, and provided with one or more vertically-arranged wick-jaws constructed to normally ride upon the inner face of the fixed section by which their inwardly-turned ends are projected inward to engage a wick upon

the draft-tube, with which both sections are concentric, and from which they are separated by an annular chamber, and exerting a constant effort to spring outward away from the draft-tube; and means mounted in the lamp-fount, passing through the fixed section, and connected with the movable section for raising and lowering the said movable section, which, when sufficiently raised brings the upper ends of the wick-jaws into range with the clearance spaces in the fixed section, permitting them to spring outward and disengage the wick, substantially as described.

3. In a central-draft lamp, the combination with the fount and central draft-tube thereof, of an air-distributer adapted to be inserted into the upper end of the said draft-tube, and a perforated annulus located near the upper

end of the draft-tube and forming a combined secondary air-distributer and drip-trough and support for the primary air-distributer, the lower end of which rests upon it, the perforations in the said annulus being located above its lower edge which is attached to the draft-tube which is constructed with one or more discharge-openings located on the level of the said lower edge of the annulus, substantially as described.

In testimony whereof we have signed this specification in the presence of two subscribing witnesses.

NIS JOHNSON.
AUGUSTUS H. JONES.
